United States Patent Office

Des. 178,729
Patented Sept. 11, 1956

178,729

COMBINED CAN PUNCH AND BOTTLE OPENER

Jesse M. Hill, San Diego, Calif.

Application February 6, 1956, Serial No. 40,058

Term of patent 14 years

(Cl. D44—29)

Fig. 2

Fig. 1

Figure 1 is a top plan view of a combined can punch and bottle opener, showing my new design; and Figure 2 is a side elevation thereof.

I claim:

The ornamental design for a combined can punch and bottle opener, as shown.
